UNITED STATES PATENT OFFICE.

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed August 15, 1927. Serial No. 212,951.

My invention relates to a fastening device, and particularly to a device intended for use as an automobile hood latch. One object of the invention is to provide a device which will be used as a hood latch and which, while serving to hold the hood down and closed, will also force the hood inwardly against its abutment and will thus hold the hood against rattling. Another object is the provision of a fastening device of the type above mentioned which shall be cheap and easy to manufacture, and simple and durable in construction. Other objects will appear from time to time in the course of the specification and claims.

I illustrate my invention more or less diagrammatically in the accompanying drawings, wherein

Figure 1 is a front elevation of one form of my hood latch, as applied to an automobile hood;

Figure 2 is a section on the line 2—2 of Fig. 1;

Figure 3 is a top plan view with the hood in section;

Figure 4 is a section along the line 4—4 of Fig. 2;

Figure 5 is a detailed section of a variant form of base member;

Figure 6 is a view, similar to Fig. 2, of a variant form of latch tube;

Figure 7 is a view similar to Fig. 6, with the latch released from the hood;

Figure 8 illustrates the latch of Figs. 6 and 7, when in normal withdrawn position;

Figure 9 is a section on the line 9—9 of Fig. 7;

Figure 10 illustrates a variant form of tube bottom;

Figure 11 illustrates the latch of Fig. 10 rotated to a different position;

Figures 12 and 13 illustrate a further variant form of latch tube, and

Figure 14 is a section on the line 14—14 of Fig. 12.

Like parts are indicated by like symbols throughout the specification and drawings.

A is a portion of an automobile frame to which may be secured an upstanding rib or abutment member A', against which abuts the lower edge B¹ of the hood B, when the hood is closed. Fastened to the hood B is a member generally designated as B², which

includes a downwardly and outwardly inclined cam portion B³, upwardly and outwardly inclined prongs B⁴, separated, for example, by the notch B⁵, a central portion B⁶ which is secured to the hood B, and a downwardly and inwardly turned bottom portion B⁷. B⁸ are any suitable securing members. 55

C is any suitable shaft or pin, terminating at the bottom in the squared beveled head C. C² generally indicates a base member having the frame engaging securing portions C³, through which may pass any suitable securing members C⁴, and the intermediate raised portion formed by the upwardly and inwardly inclined top member C⁵ and the generally vertical side walls C⁶. C⁷ is a concave generally spherical flange surrounding the aperture C⁸, through which passes the pin C. 60 65 70

The latch body proper consists of the cylindrical member D, herein shown as rolled from a single blank and with a single axial seam D¹. About the bottom of the cylinder are a plurality of ears D² adapted to be inwardly turned to engage and secure the washer D³ which is loose on the shaft C. D⁸ is a washer secured to the end of the pin C and D⁷ indicates a coil spring compressed between the washer D⁸ and the washer D³. The tendency of such spring is therefore to draw the cylinder D downwardly along the stem C. 75 80

Positioned in the upper end of the cylinder is the cylindrical plug E. Positioned above it is a latch member including a central portion E¹ overlying the plug E and the cylinder D, a handle member E², herein shown as integral with it, and a forwardly projecting portion E³ with the cross-piece E⁴. The portion E³ is adapted to penetrate the notch B⁵ between the prongs B⁴, and the cross-piece E⁴ serves to prevent forward movement of the latch portion away from the hood, once the latch is in engagement with said prongs. 85

The latch portion may be held in position in relation to the plug E and the cylinder D by being riveted to said plug E. A rivet E⁵ is indicated, which may be separate from the plug and formed to penetrate it, or which may be an upwardly projecting integral portion of the plug, upset to lock the latch in position. 90 95

G generally indicates a cam member having the axial portion G¹ wrapped about the upper edge of the cylinder D. G² indicates a pin 100 105

or rivet passing through said collar portion and an upper portion of the tube and also passing through the plug E, thus holding the entire assembly firmly together. G³ indicates an outwardly projecting nose member with the inclined face G⁴ opposed to the cam surface B³. The nose portion is continued by an inwardly turned portion G⁵ and a lip G⁶ adapted to rest against the face of the cylinder D. It may be welded or otherwise secured thereto but in the form of latch herein shown this is unnecessary and the single securing rivet G² is sufficient.

Referring to Figure 7, the latch is substantially identical with that shown in Figure 2, but the tube D, instead of being provided with the ears D², is penetrated by a pair of opposed horizontal apertures or slots H, the material of the tube being inwardly crimped therebeneath, as at H¹, in order to engage the washer D³. Note further, with reference to Figures 7 and 8, that when the latch is in its withdrawn position, as shown in Figure 8, the head of the pin C is still out of engagement with the bottom of the plug E. This proportion of parts is preferred, since it insures that the spring D⁷ will draw the latch downwardly against the abutment C⁵, thus holding it in withdrawn position.

Referring to the form of Figures 10 and 11, the bottom of the tube, instead of terminating in a single plane, as shown in Figures 7 and following, is beveled to lie in two inclined planes, as at I, I¹. The purpose of this disposition will be clear from Figure 11, which illustrates the application of one of my latches to a relatively narrow space between the hood and between a guard or fender I². In the particular form shown, the planes I and I¹ are so disposed as to permit or necessitate the rotation of the latch in such position as will bring the handle E² into parallelism with the face of the fender I².

Referring to Figures 12, 13 and 14, the lower end of the tube is apertured, as at H, but instead of being inwardly bent or crimped in the manner shown in Figure 7 the inward bending H⁵ terminates short of the bottom of the tube, the tube bottom remaining cylindrical in cross-section. Also, in the particular form of Figures 12, 13 and 14, the bottom of the tube terminates in a single plane, but this plane, instead of being at right angles to the axis of the tube, as shown in Figures 7 and following, is inclined out of such perpendicularity, as at H¹⁰, to cause the latch to project outwardly away from the hood at a greater angle or to permit the use of an abutment C⁵ having a lesser inclination in relation to the horizontal.

The form of Figure 5 illustrates a base or abutment which may be employed with the various forms of latch herein shown, and which is useful as providing a higher effective abutment. In the form shown, ears C¹⁰,

C¹⁰ project upwardly from the upwardly and inwardly inclined top member C⁵. When such form of abutment is used, it is the ears C¹⁰ which engage the bottom of the tube rather than the member C⁵ itself.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic, rather than as limiting me to my specific showing.

The use and operation of my invention are as follows:

When the closure or hood is lowered into position with its lower edge abutting against the exterior of the flange A¹, the operator may lift the latch, against the pressure of the spring D⁷ and engage the cross piece or T E⁴ with the hooks or prongs B⁴. When the handle is then released the spring draws the latch downwardly along the pin C. The result is to oppose the cam nose G³ to the outwardly inclined cam face B³. The engagement of the T with the prongs B⁴ holds the latch against outward movement away from the hood and the downward movement of the latch causes an inward movement of the hood B¹, in response to the relative movement of the opposed inclined cam surfaces B³ and G⁴. As a result the hood B¹ is not only drawn downwardly toward the base A, but is also thrust inwardly against the flange A¹ and any rattling is prevented.

As shown in the drawings the fit of the stem C in the aperture C⁸ is sufficiently loose to permit play or gyration of the stem. Thus the latch can conform itself to a certain degree of longitudinal movement of the hood B¹.

Referring to Figures 6, 7 and 8, it will be apparent that when the latch is released the spring will draw the latch downwardly against the abutment C². The pin being shorter than the distance between the lower edge of the tube and the bottom of the plug, the spring will draw the tube into the position shown in Figure 8, holding it firmly in position, withdrawn from the hood. Obviously, the angular position can be varied by varying the angle of the member C² or by varying the angle of the bottom of the tube, as shown in the form of Figures 12, 13 and 14.

Referring to Figures 10 and 11, the tilt of the latch away from the hood may be increased by giving it a one-quarter revolution from the engageable position. This result is obtained by beveling the bottom of the tube or latch body to provide a greater amount of tilt away from the hood. In some cases, where the fender of an auto-

mobile is built close to the hood, the latch position shown in Figure 10 is necessary to prevent the handle from coming in contact with the fender when in unlatched position.

- 5 When the latch is turned to permit a greater withdrawal or tilting of the latch, the handle piece E² is moved into such position that it cannot engage the fender I². Thus more room is provided to lift and lower the hood 10 without coming in contact with the latch, and without any contact of latch and fender.

In forming the latch tube, it is, of course, necessary that the washer D³ be limited against outward movement from the latch body. Figures 1 and 2 illustrate one solution of the problem, viz: the employment of inwardly turned ears. In many cases it is more practical to slot the tube, as at H, as shown in Figures 6 and following, the lower portion 20 of the tube beneath the slots being inwardly thrust into alignment with the washer. This is clearly shown in Figure 9. The indented or inwardly bent portion may extend to the bottom of the tube or, as in Figures 12, 13 25 and 14, it may not.

Figure 5 illustrates another means for varying the angle or position of the latch body when it is unlatched and at rest. The ears C¹⁰ may be made of different heights to receive the end of the body, and the body may or may not be beveled. By employing these ears, by controlling or varying their height, and by varying the plane of the bottom of the tube in its angular relation to the tube axis, 30 a great variation of position may easily be obtained.

It is preferable, but not necessary, that the pin C be of such length as to hold the latch spring in a slightly compressed condition 40 while the latch is in substantially vertical position, in order to draw the latch body downwardly against the abutment C², thus preventing it from at any time being positioned in the path of movement of the hood 45 when the hood is being raised or lowered.

I claim:

1. In a hood latch member, a latch body comprising an open ended tube, a plug member in the upper portion of said tube, a handle secured to said plug member, and including a member adapted for securing engagement with the opposed automobile hood, an engaging member adapted for cam engagement with said automobile hood, said member including a portion surrounding the upper end of said cylinder, and a securing member passing through said cylinder, plug and surrounding portion.

2. In a hood latch member, a latch body comprising an open-ended tube, a handle positioned across the upper end of said tube, and including a member adapted for securing engagement with the opposed automobile hood, a cam member adapted for cam engagement with said automobile hood,

said member including a portion surrounding the upper end of said cylinder, and a transverse securing member passing through said cylinder and said surrounding portion.

3. In a hood latch member, a latch body 70 comprising an open-ended tube, a handle positioned across the upper end of said tube, and including a member adapted for securing engagement with the opposed automobile hood, a cam member adapted for cam engagement with said automobile hood, said member including a portion surrounding the upper end of said cylinder, and a transverse securing member passing through said cylinder and said surrounding portion, said cam member including a nose portion outwardly projecting from said surrounding portion, the lower portion of said nose being recurved to abut against the side of said cylinder intermediate its ends.

4. In a hood latch member, a longitudinally seamed one-piece cylindrical latch body, a plug in the upper end thereof, a handle secured to said plug and including a hand engaging portion and a T portion, a cam member 90 mounted at the upper end of said cylinder and including a collar surrounding it and a cam nose projecting outwardly from said collar, and securing means passing through said collar, the upper end of said tube and said plug.

5. In a hood latch member, a latch body comprising an open-ended longitudinally seamed one-piece tube, the lower edge of said tube being formed with a plurality of inwardly bent tongues, a plug in the upper end of said tube, a handle secured to said plug, a cam member mounted at the upper end of the tube and including a collar surrounding it, and securing means passing through said collar, the upper end of said tube and said plug.

6. In a hood latch member, a latch body comprising an open-ended tube, a plug member in the upper portion of said tube, a handle secured to said plug member, a cam member adapted for cam engagement with said automobile hood, said member including a portion conforming to the upper end of said cylinder, and a securing member passing through said cylinder, plug and cam member.

7. In a hood latch, a latch body comprising a tube, a handle portion for the upper end of said tube, a stem on which said tube is slidably mounted, yielding means tending normally to move said tube downwardly along said stem, the lower edge of said tube being formed to lie in a plurality of planes inclined in relation to each other.

8. In a hood latch, a latch body comprising a tube, a handle portion for the upper end of said tube, a stem on which said tube is slidably mounted, yielding means tending normally to move said tube downwardly along said stem, the lower edge of said tube being formed to lie in a plurality of planes inclined

in relation to each other, said planes being inclined to the horizontal when the latch is in vertical position.

9. In a hood latch, a latch body comprising a tube, a handle at the upper end of said tube, a stem on which said tube is slidably mounted, yielding means tending normally to move said tube downwardly along said stem, including a spring compressed between said stem and the bottom of said tube, a washer positioned adjacent the bottom of said tube, against which said spring is adapted to abut, the sides of said tube being horizontally slotted beneath the normal position of said washer, the walls of the tube being inwardly compressed beneath said slots.

10. A closure latch, and a support therefor, and means for varying the angle of the latch in relation to the closure when the latch is at rest in disengaged position, and means for holding said latch outwardly inclined away from the closure when disengaged.

11. A closure latch comprising in part a support, a latch body swiveled upon said support, and means for varying the angle of said latch in relation to said closure when at rest in disengaged position, together with means for holding said latch outwardly inclined

away from the position of the closure when the latch is released.

12. A closure latch comprising in part a support, a latch body swiveled upon said support, and means for varying the angle of said latch in relation to said closure when at rest in disengaged position, together with means for holding said latch outwardly inclined away from the position of the closure when the latch is released, said varying means including a plurality of inclined beveled faces at the bottom of the latch body.

13. In a closure latch, a hollow latch body, a pin upon which said body is mounted, a guide member for said pin, and retaining means for said guide member, formed in the wall of said hollow body intermediate its ends.

14. As a new article of manufacture, a hollow body, a spring positioned in said body, and a retainer for said spring, the wall of said body being inwardly deflected intermediate its ends to limit the movement of said retainer.

Signed at Chicago, county of Cook and State of Illinois, this 10th day of August, 1927.

CHARLES B. GILMORE.
